UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

RAIL-ANCHOR.

1,251,705.

Specification of Letters Patent.

Patented Jan. 1, 1918.

Application filed September 19, 1916. Serial No. 120,918.

To all whom it may concern:

Be it known that I, JOHN W. STEPHENSON, a citizen of the United States, residing at Toledo, Lucas county, Ohio, have invented 5 new and useful Improvements in Rail-Anchors, of which the following is a specification, reference being had to the accompanying drawings, in which—

Figure 1 is an elevation showing my improved anchor applied to a rail and illustrating the rail in section; Fig. 2 is a plan thereof; Fig. 3 is an elevation of the wedge; Fig. 4 is a partial elevation similar to that of Fig. 1 but showing a modification of the 15 wedge; Fig. 5 is an elevation of a modified form of my device; Fig. 6 is a plan thereof; Fig. 7 is an elevation of the wedge, and Fig. 8 is a partial elevation, similar to Fig. 4 with a wedge of the character shown in 20 Fig. 5.

My invention relates to rail anchors and consists in a base plate and wedge constructed and arranged so as to prevent the rail from creeping.

25 Referring to the drawings, A indicates a rail section, B a base plate and C the wedge. The plate B has a rail-base engaging jaw 2 and a wedge engaging jaw 3, and a depending foot or abutment 4 intended for engagement with a tie (not shown). Underlying the edge of the rail-base on the side engaged by the wedge is a depression 5 in the plate B.

The wedge C consists of a jaw 6 which engages the upper and under faces of a 35 flange of the rail A and in a wedging face 7, inclined both to the longitudinal axis of the rail and to a horizontal plane, and engages the correspondingly-inclined inner face 8 of the jaw 3 on the base-plate B. The 40 outer end of the wedge is provided with an abutment 9 by which it is driven into place and with a lug 10 on its inner end by which the wedge may be driven out in disengaging the fastener from the rail. The lower portion 45 11 of the jaw 6 extends under the rail flange in the depression 5 of the base plate B. The faces of the jaws 2 and 6 which engage the rail flanges do not diverge as sharply as the faces of the rail which they 50 grip so that as the wedge is driven into position the two jaws will be forced slightly apart and thus exert a tight springing grip upon the rail base.

In applying the fastener to the rail the 55 plate B is first placed in position with its

jaw 2 engaging one of the base flanges of the rail. The wedge C is then driven in and as its inclined side 7 engages the corresponding inclined face 8 on the jaw 3 it is wedged against one rail flange and draws 60 the plate B and the jaw 2 against the other rail flange. At the same time the movement of the wedge C, because of the inclination of the faces 7 and 8, forces the wedge C down upon the rail base so as to hold the rail base 65 and the base of the plate B firmly together. The horizontal surface 12 on the plate, however, prevents further downward movement of the wedge C relative to the plate B so that the inward movement of the wedge 70 caused by the surfaces 7 and 8 results in a horizontal movement thereof toward the rail base.

As the wedge is driven in, the point 13 of the jaw 3 receives the maximum horizontal 75 pressure of the wedge and is in horizontal alinement with the edge of the rail so that there is no twisting action upon the wedge, and the bending stress imposed by the wedge on the jaw 3 is also reduced to a minimum 80 because the depression 5 in the base permits the application of pressure to the jaw 3 at a point substantially in alinement with the surface 12. To prevent the lower portion 11 of the jaw 6 from striking the tie when 85 the wedge has been driven into applied position, the part is cut off at 14, as is shown in Fig. 3. This is of particular advantage either where the fastener is used on an undersized rail, or where the anchor has been 90 used to such an extent that the parts have become distorted, and therefore can be driven in farther than is shown in the drawings.

Figure 1 shows the wedge C engaging the 95 lateral edge as well as the top and bottom of the rail base so that its lateral pressure upon the rail base is resisted by a direct contact with the edge of the base, as well as by the wedging grip upon top and bottom of the 100 base. In case a direct pressure upon the edge of the base is not desired, the wedge may be constructed as shown in Fig. 4, which shows the wedge gripping only the top and bottom of the rail base so that its 105 contact with the base is purely a wedging one.

In Figs. 5, 6 and 7 I have shown a modified form of my device, in which the lower portion 11² of the jaw 6² of the wedge C², 110

- instead of bearing directly upon the rail base, wedges upon a lip 15 formed upon the base member B², as is shown in Fig. 5. The portion 11² of the jaw is tapered slightly longitudinally as well as laterally, as is shown in Fig. 7 and in dotted lines in Fig. 5, so that, as the wedge is driven in, the jaw draws the lip 15 and the rail base tightly together.
- 10 In Fig. 8 I have shown a construction in which the wedge C² grips only the top and bottom of the rail base, so that, as in Fig. 4, its contact with the base is purely a wedging one.
- 15 The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.
- What I claim is:
- 25 1. In a rail anchor, a base member and a rail engaging member adapted to be driven between one part of the base member and the rail, the rail engaging member having a jaw engaging upper and lower faces of

the rail base and being held from twisting 30 by a horizontal face in substantial alinement with the bottom of the rail.

2. In a rail anchor, a base member and a rail-engaging member adapted to be driven between one part of the base member 35 and the rail, said rail-engaging member comprising a rail-engaging jaw extending within a depression in said base member, and a body portion seated upon a horizontal surface of said base member in substantial alinement with the bottom of the rail. 40

3. In a rail anchor, a base member having oppositely disposed jaws, one of said jaws having a face inclined both to the longitudinal axis of the rail and to a horizontal 45 plane, a wedge having a corresponding face bearing against the face on said jaw and being adapted to be forced thereby against the face of the rail flange, said jaw also having a horizontal bearing substantially in 50 horizontal alinement with the bottom of the rail and engaging a corresponding horizontal bearing on the wedge.

JOHN W. STEPHENSON.
